(57) **CLAIM**

The ornamental design for a bagette, as shown and described.

DESCRIPTION

FIG. 1 is a perspective view of a bagette, depicting a portion of the outer and the inner surfaces, the handles and the contrasting base of my new design;

FIG. 2 is a frontal elevation thereof;

FIG. 3 is a side elevation view thereof, typical of both sides;

FIG. 4 is a rear elevation of the bagette;

FIG. 5 is a top plan view of the bagette, depicting the contrasting base; and,

FIG. 6 is a bottom plan view of the bagette, depicting the contrasting base.
